CYLINDER FOR DRY CLEANING MACHINES

Carl S. Shields, Wickliffe, Ohio

Application May 23, 1950, Serial No. 163,732

6 Claims. (Cl. 68—143)

1

The present invention relates generally to vessels useful in cleaning operations and is more particularly concerned with a novel dry cleaning machine cylinder for containing garments while they are being cleaned by the machine.

In the conventional modern dry cleaning machine, a compartmented cylinder is provided within a housing which contains dry cleaning liquid and the clothing to be cleaned is loaded into the cylinder through doors located in one end thereof. The cylinder is typically of sheet metal construction and is provided with a large number of small openings in its sides to allow the cleaning liquid to flow in and out of the cylinder and contact the clothing therein. The cleaning results obtained with this type of machine are usually satisfactory but there are certain difficulties involved in the use of this machine and certain shortcomings of the machine itself which have persisted through its development despite determined efforts of engineers and designers to eliminate them. For one thing, garments are often damaged in the machine, being snagged or caught and torn on parts within the cylinder such as flanges or stiffening members. Furthermore, weight and manufacturing costs of the ordinary compartmented cylinder have been much higher than desired.

In accordance with the present invention, the weight and manufacturing costs of these cylinders can be substantially reduced and, at the same time, dry cleaning machine cylinders can be made in such a way that they will not damage garments charged into them, but rather will offer only perfectly smooth snag-free surfaces for contact with the garments and will have no inner flanges, braces, etc. Moreover, these results can be obtained without in any way reducing the capacity of these cylinders, their external and internal accessibility or their utility, and while substantially increasing the strength and ruggedness and the normal service life of these cylinders. Still further, because of the manner in which the cylinders of my invention are constructed, they are easier and less expensive to repair than those of the prior art.

Those skilled in the art will gain a further understanding of this invention and will recognize additional advantages thereof upon consideration of the detailed description set out below, reference being had to the drawings accompanying and forming a part of the specification, in which:

Fig. 1 is an end elevational view of a cylinder embodying this invention in a preferred form;

Fig. 2 is a fragmentary vertical sectional view of the cylinder of Fig. 1;

2

Fig. 3 is a view taken on line 3—3 of Fig. 1 and showing a back wall stiffening member in end elevation;

Fig. 4 is a view taken on line 4—4 of Fig. 1, showing in transverse cross section a front wall stiffener member;

Fig. 5 is a view taken on line 5—5 of Fig. 1, showing in transverse cross section portions of engaged peripheral parts of semi-cylindrical elements and a partition plate of the Fig. 1 cylinder;

Fig. 6 is a sectional view of the door latch means of this invention taken on line 6—6 of Fig. 1; and

Fig. 7 is a fragmentary sectional view of the access end wall portion of the cylinder, showing how the door automatically seals the access opening.

As shown in Figs. 1 and 2, a cylinder C of this invention comprises in general two substantially semi-cylindrical, perforate, open-ended sheet metal bodies 10 having relatively short, outwardly-projecting flanges 11 which extend axially of the bodies along their edges. Bodies 10 are arranged with their flanges 11 opposed and a pair 25 of sheet metal, substantially semi-circular front end plates 14 are attached to one end of bodies 10 and a second pair of sheet metal substantially semi-circular back end plates 15 are secured to the other end of bodies 10 to close cylinder C. Finally, means are provided for substantially fluid-tightly securing together opposed edges of end plates 14 and 15 and opposed flanges 11.

In the preferred embodiment of the invention illustrated, bodies 10 are provided with a larger number of perforations arranged in regular patterns in accordance with conventional practice and these bodies are made suitably from perforate flat sheet metal blanks which are bent into semi-cylindrical shape in a machine operation, after being provided with relatively short flanges 11, suitably by another conventional machine operation.

The end wall plates 14 are each provided with an access opening and a hinged door 17 and latch means 18 so that the door can be maintained closed when the cylinder is being rotated in a typical cleaning operation. The edge portions of plate 14 defining the access openings are turned inwardly and disposed generally convergingly and the edges of doors 17 are tapered inwardly in a generally complimentary manner so that when the doors are closed the edges of the doors are wedged into the access openings and sealing thereof is assured. Four circumferentially-spaced elongated sheet metal brace or stiffening members 20 are welded to the outer sides of plates 14

in radially opposed pairs around the axis of the cylinder.

Latch means 18 includes a latch lever 19 pivotally secured to each door 17 adjacent to the edge thereof remote from the hinge, and a sheet metal keeper bracket 21 secured to the end wall at a point adjacent to the access opening for receipt of the projecting end of lever 19 when the door is in closed position. Bracket 21 is formed in flanged channel shape so that its mid-portion is spaced from wall 14 but has a depressed portion or dimple 25 to bear against the said projecting end of lever 19 to lock the lever positively in closed position. Positive locking of door 17 thus is obtained by this invention without the use of springs which tend to corrode rapidly and lose their resiliency under conditions of use in dry cleaning machines. Furthermore, by virtue of this invention, adjustments may be made in the relative position and shape of dimple 25 to obtain any of a number and variety of locking effects from relatively free and loose to tight.

The opposed substantially straight edge portions of plates 14 are provided with relatively short, outwardly-projecting flanges 22, and in their mid-sections the edges and flanges are curved inwardly of their respective plates to define a substantially circular aperture 23 of relatively small diameter to receive a shaft bushing as indicated at 24.

Back wall plates 15, unlike plates 14, have no access openings or doors, and their elongated external sheet metal stiffeners 26 cover wider areas than stiffeners 20. Plates 15, however, are of substantially the same general shape as plates 14 and have relatively short outwardly-extending flanges 28 along their opposed edges and these flanges and said edges cooperate to define an axial aperture 29 to receive a shaft bushing or the like as described above.

Plates 14 and 15 are suitably manufactured from sheet metal stock by standard machine tools and operations, both types being cut, flanged and drilled in the same manner and design and plates 14 receiving additional treatment to provide their additional features as stated above.

Also in the preferred embodiment of this invention, partition means are provided within the cylinder including two diametrically-opposed metal plates 30 of substantially the same shape and dimensions, the outer edge portions 31 of which are disposed between opposed flanges 11, 22 and 28. Inner edge portions 32 of partition plates 30 are secured in spaced relation to each other by means of a pair of opposed semi-cylindrical flanged metal plates 34 and rivets 35 which extend through opposed flanges of plates 34 and edge portions 31 disposed between said flanges. The cylindrical space described by plates 34 is substantially in register with apertures 23 and 29 to receive a drive shaft or trunnions (not shown) to support the cylinder. Plates 30 are secured to the cylinder by means of welds 40 (Fig. 5) which serve also to secure plates 14 and 15 and semi-cylindrical bodies 10 in position with respect to each other. Because welds 40 extend substantially around the cylinder on its mid-section, the cylinder has all the stiffness and strength of the substantially heavier and more expensive cylinders of the prior art.

Having thus described the present invention so that those skilled in the art may be able to understand and practice the same, I state that what I desire to secure by Letters Patent is defined in what is claimed.

What is claimed is:

1. A dry cleaning machine cylinder for containing garments to be cleaned comprising two substantially semi-cylindrical, perforate, open-ended sheet metal bodies, outwardly projecting flange portions extending axially along the edges of said bodies, said bodies being arranged with said flange portions opposed to define an open-ended cylinder, a pair of sheet metal, substantially semi-circular end plates attached to each end of the cylinder and cooperating to substantially close the ends of said cylinder, the diametral edges of the end plates being oppositely disposed, partition means including a metal plate in the cylinder having outer edge portions disposed between the opposed edges of the end plates and the opposed outwardly extending flange portions of the said bodies, means for substantially fluid-tightly securing said partition plate to the said opposed edges and flange portions, openings in the end plates at one end of the cylinder, the plates being formed with integral inwardly-directed portions cooperating with the corresponding portions of the end plates, the door members and the inwardly directed portions acting as stiffeners for the cylinder.

2. A dry cleaning machine cylinder for containing garments to be cleaned comprising two substantially semi-cylindrical, perforate, open-ended sheet metal bodies, outwardly projecting flange portions extending axially along the edges of said bodies, said bodies being arranged with said flange portions opposed and cooperating to define an open-ended cylinder, a pair of sheet metal, substantially semi-circular end plates attached to each end of the cylinder and cooperating to substantially close the ends of said cylinder, outwardly projecting flanges extending along opposed edges of said end plates, partition means including a plurality of metal plates in the cylinder having edge portions disposed between the outwardly projecting flanges of the end plates and the opposed outwardly extending flange portions of the said bodies, means for substantially fluid-tightly securing said partition plates to said opposed end plate and body flange portions, openings in the end plates at one end of the cylinder, the plates being formed with converging inwardly-directed portions adjacent the opening, and the converging portions comprising an integral part of the end plate, door members having converging portions cooperating with the corresponding portions of the end plates, and a plurality of radially directed sheet metal members attached to the end plates, the door and the converging portions and the radially directed members acting as stiffeners for the cylinder.

3. A dry cleaning machine cylinder for containing garments to be cleaned comprising two substantially semi-cylindrical, perforate, open-ended sheet metal bodies, outwardly projecting flange portions extending axially along the edges of said bodies, said bodies being arranged with said flange portions opposed and cooperating to define an open-ended cylinder, a pair of sheet metal, substantially semi-circular end plates attached to each end of the cylinder and cooperating to substantially close the ends of said cylinder, outwardly projecting flanges extending along opposed edges of said end plates, hub means secured to the end plates coaxially with the cylinder and aligned with central recesses in the end plates, partition means including two spaced plates in the cylinder secured to the hub

means and having outer edge portions disposed between the opposed outwardly projecting flanges of the end plates and the opposed outwardly extending flange portions of the said bodies and the plates of the partition means having spaced inner edge portions, means fluid-tightly securing said partition plates to said opposed end plate and body flange portions, opposed semi-cylindrical flanges joining the inner edge portions of the partition plate and defining an aperture aligned with the recesses, and a plurality of radially directed sheet metal members attached to the end plates, the partition members and radially extending members serving to stiffen the cylinder.

4. A dry cleaning machine cylinder for containing garments to be cleaned comprising two substantially semi-cylindrical, perforate, open-ended sheet metal bodies, outwardly projecting flange portions extending axially along the edges of said bodies, said bodies being arranged with the flanged portions opposed to define an open-ended cylinder, a pair of sheet metal substantially semi-circular end plates attached to each end of the cylinder and cooperating to substantially close the ends of said cylinder, partition means including a plurality of metal plates in the cylinder having outer edge portions disposed between opposed edges of the end plates and said opposed outwardly extending flanged portions of the said bodies, and the partition plates having spaced inner edge portions, means substantially fluid tightly securing said partition plate to the said opposed edges and flanged portions, central recesses in the end plates forming registered openings and defining an axis of rotation for the cylinder, and opposed, semi-cylindrical flanges joining the inner edge portions of the partition plate and defining a cylindrical aperture aligned with the openings in the end plates.

5. A dry cleaning machine cylinder for containing garments to be cleaned comprising two substantially semi-cylindrical, perforate, open-ended sheet metal bodies, outwardly projecting flange portions extending axially along the edges of said bodies, said bodies being arranged with the flanged portions opposed and cooperating to define an open-ended cylinder, a pair of sheet metal substantially semi-circular end plates attached to each end of the cylinder and cooperating to substantially close the ends of said cylinder, outwardly projecting flanges extending along opposed edges of said end plates, partition means including a plurality of metal plates in the cylinder having outer edge portions disposed between

55

the opposed flanges of the end plates, and the opposed outwardly extending flanged portions of the said bodies and the partition plates having spaced inner edge portions, means substantially fluid tightly securing said partition plates to said opposed end plate and body flange portions, opposed semi-cylindrical flanges joining the inner edge portions of the partition plates, and openings in the end plates at one end of the cylinder, the plates being formed with integral inwardly directed portions around the opening.

6. A dry cleaning machine cylinder for containing garments to be cleaned comprising two substantially semi-cylindrical, perforate, open-ended sheet metal bodies, outwardly projecting flange portions extending axially along the edges of said bodies, said bodies being arranged with the flanged portions opposed and cooperating to define an open-ended cylinder, a pair of sheet metal substantially semi-circular end plates attached to each end of the cylinder and cooperating to substantially close the ends of said cylinder, outwardly projecting flanges extending along opposed edges of said end plates, partition means including a plurality of metal plates in the cylinder having outer edge portions disposed between the opposed flanges of the end plates and the opposed outwardly extending flanged portions of the said bodies, and the partition plates having spaced inner edge portions, means substantially fluid tightly securing said partition plates to said opposed end plate and body flange portions, opposed semi-cylindrical flanges joining the inner edge portions of the partition plates, openings in the end plates at one end of the cylinder, the plates being formed with converging inwardly directed portions around the opening, and a plurality of radially extending members attached to the end plates, the partition, inwardly directed portions and radially extending members serving to stiffen the cylinder.
